UNITED STATES PATENT OFFICE.

RICHARD D. GALLAGHER, JR., OF NEW YORK, N. Y.

CAR-COUPING.

No. 927,138.

Specification of Letters Patent.

Patented July 6, 1909.

Application filed June 20, 1908. Serial No. 439,588.

To all whom it may concern:

Be it known that I, RICHARD D. GALLAGHER, Jr., a citizen of the United States, residing in the city, county, and State of New York, have invented certain new and useful Improvements in Car-Couplers; and I do hereby declare the following to be a full, clear, and exact description of the same, reference being had to the accompanying 10 drawings, forming a part of this specification, and to the figures and letters of reference marked thereon.

This invention relates to car couplers of the so-called "Janney" or M. C. B. type of 15 coupler.

The object of the invention is to provide an improved operating mechanism, whereby the coupler is rendered fully automatic with the employment of few and simply constructed 20 parts so arranged in the coupler head as to give a maximum strength and resistance to destruction under excessive strains.

A further object of the invention is to provide a structure which may be utilized to the 25 greatest advantage in connection with the so-called radial mounting of the couplers, without permitting appreciable slack or pivotal action between coöperating couplers.

A further object of the invention is to provide an improved form of locking mechanism for the knuckle embodying a means whereby the lock may be set in its open or unlocking 30 position and automatically tripped by the movement of the knuckle itself when cars are separated, thereby restoring the parts to 35 position for automatic reengagement when the cars are again brought together.

Referring to the accompanying drawings: Figure 1 is a top plan view of a coupler embodying the present improvements, a portion 40 of the under frame of the car being indicated in dotted lines. Fig. 2 is a sectional plan view embodying the unlocking mechanism and omitting the car frame. Fig. 3 is a 45 vertical section taken on the irregular line 3—3 of Fig. 2. Fig. 4 is a section of the coupler head and working parts, said section being taken on the line 4 of Fig. 2. Fig. 5 is a plan view of the knuckle, and Fig. 5^a is 50 a vertical section on the line 5—5 of Fig. 5. Fig. 6 is a top plan view of the lock set, and Fig. 7 is an elevation of the same, looking in the direction of the arrow 7 in Fig. 6. Fig. 8 is a detail half-section and elevation of a 55 portion of the head, the lower end of the knuckle pin and cup for retaining the pin in

place. Fig. 9 is a sectional plan showing in full lines the knuckle in normal position with the lock disengaged and held by the lock set and in dotted lines the knuckle partially open 60 and the lock set moved into position for releasing the lock. Fig. 10 is a similar view with the knuckle open in full lines and with the knuckle partly returned to closed position in dotted lines, the dotted lines also indicating the positions of the lock and lock set during the return movement of the knuckle. 65

Similar characters of reference indicate the 70 same parts in all the views.

The coupler head or rigid integral portion of the coupling is indicated by the letter A, and it will be understood that this head may be provided with a shank A' of any suitable character, but, as shown, the shank is adapted 75 to form a portion of a centering mechanism A², the details of which it is unnecessary to describe, inasmuch as the specific construction forms no part of the invention of the present application. Pivotal mounted 80 in the head at its forward end, is a knuckle B, shown in detail in Figs. 5 and 5^a. The forward hook end of the knuckle preferably conforms in contour lines to the contour lines of the approved types of M. C. B. couplers 85 now in common use, and the same is true of those portions of the face of the head with which the coöperating knuckle is adapted to contact or engage. The rear end of the shank B' of the knuckle is given a proper 90 conformation for coöperation with the horizontally swinging lock set, thus, as shown in said Figs. 5 and 5^a, the said shank is provided at b with a curved lock engaging face, the 95 arc of the curve corresponding to the arc traversed by the engaging face of the lock C, indicated in Fig. 2. The shank B' is further extended in the form of a hook b', adapted to pass around or behind a boss or hub d, usually constituting one of the pin supports for 100 the pivot pin of the lock set, as will be hereinafter described. The end face b² is made substantially concentric with the axis of the knuckle and is adapted to receive or support the lock during a portion of the forward 105 opening and all of the closing movements of the knuckle, as will also be hereinafter described. A cam adapted to coöperate with the lock set extends partially around the hub of the knuckle, one face b³ of said cam being 110 made substantially concentric with the axis of the knuckle and the other face b⁴, which

merges into the face b^3 , being made concentric or of diminishing radius toward the front or outer end of the knuckle, whereby the lock set may be held without movement on its axis during that portion of the movement of the knuckle near the outer extreme of its movement and will be permitted to swing forwardly on its axis during that portion of the movement of the knuckle in proximity to its closed position.

The lock set illustrated in Figs. 2 and 3 and in detail in Figs. 6 and 7, is an irregularly shaped body having a hub D adapted to be pivotally mounted on a pin D', riveted in the boss d at the bottom of the coupler head and in a corresponding boss d' at the top of the coupler head. The lock set is provided with a knuckle-cam engaging face D², and with a lock engaging face or projection D³, the portion of the periphery of the lock set forward of the lock engaging projection or face D³ being made concave at D⁴, the radius of the curve being such that the lock set is moved rearwardly a slight distance by the lock when the latter is swung from the position indicated in Fig. 2, into its unlocking position, whereby the lock set is adapted to drop in behind the lock for retaining it in such unlocking position, as indicated in Fig. 9. For giving ample support to the lock set, it is conveniently provided with arc or other properly shaped top and bottom projections or wear-faces D⁵ and D⁶, such projections or wear faces being adapted to contact or co-operate with corresponding faces or projections d⁵ at the top of the coupler head, Fig. 3, and d⁶ at the bottom of the coupler head, Fig. 2, the latter projection also serving as a guide and support for a Van Dorn hook in case the coupler is used in co-operation with a Van Dorn coupler such as is now in common use.

The lock or latch C, Figs. 2 and 3, is pivotally mounted on a vertical lock pin C', journaled in the coupler head and at its outer end is provided with a knuckle engaging face c and a lock set engaging projection c'. The lock pin C' is provided with an operating arm or lever C² and a coiled spring C³, usually housed within the hub of the lever for returning the lock to its locking position. The lever C² is connected through a link c³ with a bell crank lever C⁴, pivotally mounted on the shank A' of the coupler in proximity to its axis, and the opposite end of the bell crank lever is loosely connected through a link C⁵, bell crank C⁶, and link C⁷, with a cranked operating shaft C⁸, usually extending up through the buffer beam into convenient position for operation by a brakeman, the loose connection being provided, in order to permit of the radial movement of the coupler, without disturbing the position of the lock. Such loose connection may conveniently consist of a slot and pin connection c⁵, the range of free movement, however, being such

that the operating shaft will take up the free movement preliminary to the movement of the lock, as will be readily understood.

In the preferred arrangement and construction of the cars a single spring is employed, both for advancing or holding the lock set up to its work, and for opening the knuckle when released from the lock. This spring, which is preferably of the coiled type, is conveniently mounted on a spool F, carried by a through pin f in the coupler head in rear of the knuckle shank, one end G of the spring being extended to engage the rear side of the lock set and the opposite end G' of the spring being extended and bent angularly to engage in a recess g' in the knuckle at a point in rear of its axis. Extreme forward movement of the end G' of the spring, as for instance when the knuckle is removed, is limited by its contact with a projection of flange g², Fig. 4, extending upwardly from the bottom of the coupler head, thus the end of the spring will be normally held in position to properly enter the recess in the knuckle when the latter is placed in position in the coupler head without thought or attention on the part of the workmen.

As has been before stated herein, the hook B' of the knuckle passes behind the hub d for the lock set, and thus would retain the knuckle in position in the head, even though its pivot pin were broken or lost, but in order to still further guard against the withdrawal of the knuckle in case of accidental breakage or loss of the pin, the upper projecting edge of the cam at b³, (Fig. 5^a), is adapted to pass behind a concentric shoulder a³, shown in section in Fig. 4, and in dotted lines in Fig. 1.

The coupler of the present invention is primarily designed for use on passenger coaches adapted for suburban, as well as through line traffic and in cars adapted for such use there is little available space for the coupling and attachments appurtenant thereto. For instance, it is difficult to insert or remove the pivot pins of the knuckle, because of interference with other portions of the car structure, and it is likewise desirable that projections above and below the body of the coupler heads should be avoided. In the present arrangement, I have provided a means whereby the pivot pin may be securely held in place, may be removed downwardly and does not project above the upper face of the head. Such securing means embodies a cup H, Fig. 8, adapted for the reception of the lower end of the knuckle pin I. The cup is provided with a flange h adapted to pass transversely of the pin into an open-sided socket or recess II' in the bottom face of the coupler head, and when seated in said socket or recess the cup cavity aligns with the pin bearings, and the pin having been previously inserted, is free to drop into the cup by which it is retained in

place and in turn itself retains or locks the cup in its socket or bearing in the head. The bottom of the cup is conveniently provided with an aperture of less diameter than the 5 pin through which drainage may take place and through which an instrument may be inserted for lifting the pin when it is desired to remove the cup, pin and knuckle.

As appurtenant to, but not constituting 10 any portion of the invention of the present application, but forming the subject-matter of a contemporaneous application, the coupler mechanism heretofore illustrated and described forms parts of a coupler head having 15 an extended guard arm K on the front side of the knuckle hook and an inclined face projection or guard arm abutment L on the rear side of the knuckle hook. The extremity of the guard arm K is preferably made so as to 20 yield slightly under considerable resistance, and the guard arm and projection L of co-operating couplers are adapted to contact both for positioning the knuckles with relation to each other and for holding the 25 couplers in alignment. This construction relieves shock which would occur when the couplers are brought together, admits of a certain limited amount of flexibility in the coupling and permits of the making of a very tight coupling, inasmuch as the coupler mechanism may 30 be brought close together.

The operation of the working parts of the coupler will be readily understood from an inspection of Figs. 2, 9 and 10. In Fig. 2 35 the parts are shown with the knuckle in its closed position, or in the position it would occupy when in engagement with a co-operating knuckle. In Fig. 9, in full lines, the lock has been moved through the instrumentality before mentioned so as to cause the 40 lock set to be first moved toward the rear against the tension of its spring, and then released from the projection on the lock so as to advance in front of the projection, 45 thereby retaining the lock in its unlocking position. The knuckle in moving from the position indicated in full lines to that indicated in dotted lines in Fig. 9, operates through the cam b^4 to again move the lock 50 set rearwardly a sufficient distance to release the lock, but in making its forward movement the shank or inner face of the knuckle moves in front of the lock and when the latter is released from the lock set it swings 55 against the end face of the knuckle and is prevented from further forward movement, although the knuckle is free to continue its forward movement to the position indicated in full lines in Fig. 10, where it is shown as 60 fully open. During the latter portion of its movement the lock set rides upon the concentric portion of the cam face and neither resists nor aids in the movement of the knuckle when it has reached the position 65 indicated in dotted lines in Fig. 10, the lock

set still working against the face of the cam swings forwardly, but does not again engage and hold the lock inasmuch as the projection c' has advanced in front of the lock set and prevents further forward movement of 70 the latter. Any pressure exerted by the spring of the lock set itself only tends to turn the lock into its locking position and this movement of the lock immediately takes place as soon as the knuckle has returned to 75 the position indicated in Fig. 2. The arrangement is such that the lock may be moved to its unlocking position and left so that the cars will automatically uncouple when drawn apart, but the parts will automatically reposition themselves ready for reengagement when the knuckle is again turned to its closed position, as by the entry of a co-operating knuckle in the well understood manner. By removing the knuckle pin it is 80 obvious that the forward turning movement of the knuckle may be continued and the knuckle entirely removed without affecting the adjustment or position of the remaining parts of the coupler. The knuckle may be 85 reinserted with equal facility, and when reinserted, the concentric projection or cam and the hook at the inner end of the knuckle insure its proper entry and the proper reengagement of the end of the spring with the 90 rear side of the knuckle. The spring operates to throw the knuckle to its open position should it be desired simply to set the coupling for engagement with a co-operating coupling, and hence there is no need for a 100 trainman to pass between the cars for any purpose.

Having thus described the invention, what is claimed as new and desired to be secured by Letters-Patent, is:

1. In a car coupler, the combination with the coupler head, horizontally swinging knuckle mounted therein and horizontally swinging lock co-operating with the inner part of the knuckle for holding the same in 110 closed position, of a horizontally swinging lock set co-operating with the lock to hold the same in its unlocking position, and a cam on the knuckle co-operating with the lock set for moving the same to release the lock. 115

2. In a car coupler, the combination with the coupler head, horizontally swinging knuckle mounted therein and horizontally swinging lock co-operating with the inner part of the knuckle, of a horizontally swinging lock set co-operating with the lock to hold the same in its unlocking position, and a cam of forwardly diminishing radius on the knuckle co-operating with the lock set during the opening movement of the knuckle to release 120 the lock ready for subsequent reengagement with the knuckle. 125

3. In a coupler, the combination with the coupler head, horizontally swinging knuckle mounted therein and horizontally swinging 130

- lock coöperating with the inner part of the knuckle to hold the same in its closed position, of a horizontally swinging lock set, co-operating shoulders on the lock and lock set, whereby in one position the lock set retains the lock and in another position the lock retains the lock set against forward movement, and a cam on the knuckle for moving the lock set to release the lock.
10. 4. In a coupler, the combination with the coupler head, a horizontally swinging knuckle therein and horizontally swinging lock coöperating with the inner part of the knuckle, of a horizontally swinging lock set co-operating with the lock to hold the same in its unlocking position and a cam on the knuckle having a concentric face and a face of diminishing radius merging into the said concentric face for coöperation with the lock set in moving the latter to release the lock and hold the lock set against forward movement.
15. 5. In a coupler, the combination with the coupler head, horizontally swinging lock co-operating with the inner part of the knuckle, of a horizontally swinging lock set, an inclined face on said lock set with which the lock coöperates to move the lock set rearwardly, a shoulder on the lock set for holding the lock in its unlocking position, and a cam on the knuckle coöperating with the lock set to move the same rearwardly and release the lock from said shoulder.
20. 6. In a coupler, the combination with the coupler head, horizontally swinging knuckle mounted therein and horizontally swinging lock coöperating with the inner part of the knuckle, of a horizontally swinging lock set having a path of movement parallel with and overlying the path of movement of the inner part of the knuckle, coöperating faces on the lock set and lock, whereby the latter is held in its unlocking position and coöperating faces on the knuckle and lock set, whereby the lock set is moved rearwardly by the opening of the knuckle to release the lock ready for reengagement.
25. 7. In a car coupler, the combination with the coupler head, horizontally swinging knuckle mounted therein and having an inwardly extending shank formed into a rearwardly opening hook and the horizontally swinging lock coöperating with the shank of the knuckle, of a lock set overlying the shank of the knuckle, a pivot hub for the lock set with which the rearwardly opening hook of the shank coöperates, and a cam on the knuckle for moving the lock set rearwardly to release the lock.
8. In a car coupler, the combination with the coupler head, horizontally swinging knuckle mounted therein and horizontally swinging lock coöperating with the shank of the knuckle, of a horizontally swinging lock set overlying the shank of the knuckle, a pivot hub for said lock set behind which the shank of the knuckle passes, a cam projection on the knuckle for moving the lock set to release the lock, and a shoulder on the coupler head with which said cam projection coöperates, substantially as described.
9. In a coupler, the combination with the coupler head, horizontally swinging knuckle mounted therein having an inwardly extending shank, and a horizontally swinging lock for coöperation with the said shank, of a horizontally swinging lock set movable in parallelism with the shank of the knuckle and overlying the same, a cam on the knuckle for moving the lock set to release the lock and coöperating bearing faces on the lock set and top and bottom of the coupler head respectively at points remote from the axis of the lock set.
10. In a coupler such as described, the combination with the coupler head, horizontally swinging knuckle, horizontally swinging lock, and horizontally swinging lock set with coöperating faces on said parts, whereby the lock is retained in its unlocking position by the lock set, and the lock set is moved by the knuckle to release the lock, of a single spring mounted in the coupler head and coöperating at one end with the knuckle to open the same and at the opposite end with the lock set for advancing the same to its operative position.
11. In a coupler such as described, the combination with the coupler head, horizontally swinging knuckle, horizontally swinging lock and horizontally swinging lock set, of a spring mounted in the coupler head and coöperating with the lock set and knuckle, and a shoulder in the coupler head forming a stop for holding the end of the spring in position to coöperate with an entering knuckle.
12. In a coupler, the combination with the coupler head, horizontally swinging knuckle mounted therein, horizontally swinging lock and horizontally swinging lock set, all pivotally mounted on independent axes, of a coiled spring mounted in the coupler head and coöperating at one end with the lock set and at the other end with the knuckle, substantially as described.
